DESIGN FOR A COMBINATION PENCIL, RULER, AND LEVEL

Morris Gurtov, New York, N. Y.

Application January 25, 1941, Serial No. 98,386

Term of patent 7 years

To all whom it may concern:

Be it known that I, Morris Gurtov, a citizen of the United States and a resident of the city of New York, Borough of Bronx, county of Bronx, and State of New York, have invented a new, original, and ornamental Design for a Combination Pencil, Ruler, and Level, of which the following is a specification, reference being had to the accompanying drawing, forming part thereof, in which—

Fig. 1 is a top plan view of a combination pencil, ruler and level embodying my design;

Fig. 2 is a side view thereof;

Fig. 3 is a bottom view thereof;

Fig. 4 is an end view thereof.

I claim:

The ornamental design for a combination pencil, ruler, and level, substantially as shown.

MORRIS GURTOV.
